Primary Examiner—Alan P. Douglas*Assistant Examiner*—Antoine D. Davis*Attorney, Agent, or Firm*—Keck, Mahin & Cate**[57]****CLAIM**

The ornamental design for a drilling machine for railroad rail, as shown and described.

DESCRIPTION

FIG. 1 is a left side perspective view of a drilling machine for railroad rail showing my design;

FIG. 2 is a right side perspective view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a top plan view thereof.

FIG. 1

FIG. 2

FIG. 3

FIG. 4

FIG. 5

FIG. 6

FIG. 7
